IGNITION SYSTEM

Wayne J. Morrill, Fort Wayne, Ind., assignor to
General Electric Company, a corporation of
New York

Application March 12, 1943, Serial No. 478,921

10 Claims. (Cl. 315—259)

My invention relates to ignition systems and more particularly to low voltage high frequency systems of this type.

An object of my invention is to provide an improved ignition system.

Another object of my invention is to provide an improved high frequency ignition system which utilizes a resonant circuit in the distribution circuit of the system to produce a spark discharge at the spark plugs.

Further objects and advantages of my invention will become apparent and my invention will be better understood from the following description referring to the accompanying drawing, and the features of novelty which characterize my invention will be pointed out with particularity in the claims annexed to and forming part of this specification.

The drawing schematically illustrates an ignition system provided with an embodiment of my invention.

Referring to the drawing, I have shown an ignition system adapted to be provided with a high frequency current energization from any suitable source 10 across which a capacitor 11 is connected. This source of high frequency current is connected to a distributor provided with a plurality of transformers equal in number to the number of spark plugs in the system. Each of these transformers is provided with a primary winding 12 arranged about a leg of a transformer core 13 and inductively coupled with a transformer secondary winding 14 arranged about another leg of the transformer core 13. The primary windings 12 are shown all connected in series with each other across the source of high frequency current 10 but may be connected in parallel if desired. Each secondary winding 14 is connected to its respective distribution circuit which includes a capacitance 15 and an inductance formed by a transformer having a primary winding 16 and a secondary winding 17 connected across a spark plug 18. The capacitance 15 may be the distributed capacitance of the various parts of the system or may also include a separate capacitor connected in the circuit. The distributor is provided with a rotatable coupling member 19 formed of magnetic material which is adapted periodically to close the magnetic circuit between the legs of each transformer core 13 consecutively to complete the magnetic circuit of the distributor transformer and subsequently to insert a magnetic shunt formed by a leg 20 on the transformer core 13. The values of capacitance and inductance in the

distribution circuit are made such that the change in the inductance in each distribution circuit by the insertion of the magnetic shunt 20 provides a resonant circuit with each respective distributor transformer to produce a spark discharge periodically at each respective spark discharge device or spark plug 18. The spark plug transformer is adapted to raise the voltage supplied to it by its respective distributor transformer and to provide a peak voltage when its distribution circuit becomes resonant, as described above, to produce an electrical breakdown of its respective spark plug. In this manner, I have provided an ignition system in which the distributor is arranged to connect a high frequency source of current inductively to a distribution circuit and also to provide for the distribution of ignition current to each spark plug of the system without any intermediate electrical spark device or circuit breaker requiring sparking electrodes or contactors, as the entire system is coupled together and operable by electromagnetic inductive circuits.

While I have illustrated and described a particular embodiment of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States is:

35 1. An ignition system including a distribution circuit with a spark discharge device, a transformer connected to said spark discharge device, capacitance in said distribution circuit, and means including a distributor for inductively connecting a source of high frequency current to said distribution circuit, said distributor means including a member for changing the inductance of said distribution circuit providing a resonant circuit with said spark discharge device producing a spark discharge at said discharge device.

40 2. An ignition system including a distributor circuit with a spark discharge device, a capacitance in said distribution circuit, a source of high frequency current, and means including a distributor having a transformer for connecting said source of high frequency current to said distribution circuit, said distributor means including a magnetic shunt and a rotatable magnetic coupling member for varying the inductance of 45 said distribution circuit to provide a resonant circuit.

cuit with said spark discharge device producing a spark discharge at said discharge device.

3. An ignition system including a distribution circuit with a spark discharge device, inductance in said distribution circuit, capacitance in said distribution circuit, and means including a distributor for inductively connecting a source of high frequency current to said distribution circuit, said distributor means being arranged periodically to vary the inductance of said distribution circuit for periodically providing a resonant circuit with said spark discharge device to produce a spark discharge at said discharge device.

4. An ignition system including a distribution circuit with a spark discharge device, a capacitance in said distribution circuit, a source of high frequency current, and means including a distributor for inductively connecting said source of high frequency current to said distribution circuit, said distributor means including a rotatable magnetic coupling member for varying the inductance of said distribution circuit to provide a resonant circuit with said spark discharge device producing a spark discharge at said discharge device.

5. An ignition system including a distribution circuit with a spark discharge device, a transformer connected to said spark discharge device, a capacitance connected in series with said transformer, a source of high frequency current, and means including a distributor for inductively connecting said source of high frequency current to said distribution circuit, said distributor means including a rotatable member for varying the inductance of said distribution circuit to provide a resonant circuit with said spark discharge device producing a spark discharge at said discharge device.

6. An ignition system including a distribution circuit with a spark discharge device, a capacitance in said distribution circuit, a source of high frequency current, and means including a distributor having a transformer for connecting said source of high frequency current to said distribution circuit, said distributor means including a magnetic shunt and a rotatable member adapted to complete periodically the magnetic circuit of said distributor transformer and to insert said magnetic shunt in said distributor transformer magnetic circuit for varying the inductance of said distribution circuit to provide periodically a resonant circuit with said spark discharge device connected to said distributor transformer and to produce a spark discharge at said discharge device.

7. An ignition system including a distribution circuit with a spark discharge device, a transformer connected to said spark discharge device, capacitance in said distribution circuit, a source of high frequency current, and means including a distributor having a transformer for connecting said source of high frequency current to said distribution circuit, said distributor means including a magnetic shunt and a rotatable magnetic coupling member adapted to complete the magnetic

circuit of said distributor transformer and subsequently to insert said magnetic shunt in said distributor transformer magnetic circuit for varying the inductance of said distribution circuit to provide a resonant circuit with said spark discharge device connected to said distributor transformer and to produce a spark discharge at said discharge device.

8. An ignition system including a distribution circuit with a spark discharge device, a transformer connected to said spark discharge device, a capacitance connected in series with said transformer, a source of high frequency current, and means including a distributor having a transformer for connecting said source of high frequency current to said distribution circuit, said distributor means including a magnetic shunt and a rotatable magnetic coupling member adapted to complete the magnetic circuit of said distributor transformer and to insert said magnetic shunt in said distributor transformer magnetic circuit for varying the inductance of said distribution circuit to provide a resonant circuit with said spark discharge device connected to said distributor transformer and to produce a spark discharge at said discharge device.

9. An ignition system including a distribution circuit with a spark discharge device, a transformer connected to said spark discharge device, a capacitance in said distribution circuit, and means including a distributor having a transformer for connecting a source of high frequency current to said distribution circuit, said distributor means including a magnetic shunt and a rotatable magnetic coupling member adapted to complete the magnetic circuit of said distributor transformer and subsequently to insert said magnetic shunt in said distributor transformer magnetic circuit for changing the inductance of said distribution circuit to provide a resonant circuit with said spark discharge device connected to said distributor transformer and to produce a spark discharge at said discharge device.

10. An ignition system including a distribution circuit with a spark discharge device, a transformer connected to said spark discharge device, capacitance in said distribution circuit, a source of high frequency current, and means including a distributor having a transformer for connecting said source of high frequency current to said distribution circuit, said distributor means including a magnetic shunt and a rotatable magnetic coupling member adapted periodically to complete the magnetic circuit of said distributor transformer and subsequently to insert said magnetic shunt in said distributor transformer magnetic circuit for periodically coupling said distribution circuit to the source of current and for periodically changing the inductance of said distribution circuit to provide a resonant circuit with said spark discharge device connected to said distributor transformer and to produce a spark discharge at said discharge device.
